US00D960285S

(12) **United States Design Patent** (10) **Patent No.:** **US D960,285 S**
(45) **Date of Patent:** **** Aug. 9, 2022**

(54) **LUBRICATOR**

(71) Applicant: **SMC CORPORATION**, Tokyo (JP)

(72) Inventors: **Tadamitsu Higaki**, Moriya (JP);
Tomokazu Ueno, Tsukubamirai (JP)

(73) Assignee: **SMC CORPORATION**, Tokyo (JP)

(**) Term: **15 Years**

(21) Appl. No.: **29/739,458**

(22) Filed: **Jun. 25, 2020**

(30) **Foreign Application Priority Data**

Dec. 26, 2019 (JP) 2019-028882

(51) **LOC (13) Cl.** **23-01**

(52) **U.S. Cl.**

USPC **D23/207**

(58) **Field of Classification Search**

USPC D23/207, 209, 235, 341, 358, 363-365;

D15/5

CPC B01D 46/0002; B01D 46/10; F02M 35/04;

(57) **CLAIM**

The ornamental design for a lubricator, as shown and described.

DESCRIPTION

FIG. 1 is a front, top and left side perspective view of a lubricator showing our new design;

FIG. 2 is a rear, bottom and right side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof;

FIG. 8 is a right side view thereof; and,

FIG. 9 is a partial cross sectional view taken along the line 9-9 of FIG. 5.

The broken lines depict portions of the lubricator that form no part of the claimed design.

1 Claim, 9 Drawing Sheets
